(57) **CLAIM**

We claim the ornamental design for an MRI-compatible therapeutic gas delivery cart, as shown and described.

DESCRIPTION

FIG. 1 is a top, front, and left-side perspective view of an MRI-compatible therapeutic gas delivery cart showing our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof;

FIG. 7 is a bottom, front, and right-side perspective view thereof;

FIG. 8 is a top, rear, and left-side perspective view thereof;

FIG. 9 is a bottom, rear, and right-side perspective view thereof; and,

FIG. 10 is another top, front, and left-side perspective view thereof, in which equipment is mounted on the cart in order to illustrate a sample environment.

The broken lines in the figures show portions of the cart which form no part of the claimed design.

The broken line showing of the equipment mounted on the cart in FIG. 10 is for environmental purposes only and forms no part of the claimed design.

Any areas of the cart that are not shown in the drawings form no part of the claimed design.
